(57) CLAIM

The ornamental design for an adjustable flexible sander, as shown and described.

DESCRIPTION

FIG. 1 is a front elevational view of the adjustable flexible sander showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a perspective view taken from above and to the left;
FIG. 8 is a front elevational view of an alternatively preferred embodiment of my new design;
FIG. 9 is a rear elevational view thereof;
FIG. 10 is a left side elevational view thereof;
FIG. 11 is a right side elevational view thereof;
FIG. 12 is a top plan view thereof;
FIG. 13 is a bottom plan view thereof; and,
FIG. 14 is a perspective view taken from above and to the left thereof.
